MORTAR APPLICATOR

William C. Kleman, Jr., Miami Beach, Fla.

Application July 11, 1947, Serial No. 760,249

3 Claims. (Cl. 72—128.)

1

The present invention relates to mortar applicators and it consists in the combinations, constructions and arrangements of parts herein described and claimed.

It is an object of the present invention to provide a mechanism for the application of mortar which is simple in construction and efficient in its operation.

Another object of the invention is the provision of an applicator for mortar which will permit an unskilled person to apply mortar to bricks, masonry and the like in a proper manner and with much greater speed than skilled workers using conventional tools.

Another object of the invention is the provision of a device of the character above referred to which may be utilized in conjunction with a conventional mortar board.

A further object of the invention is the provision of a mechanism for applying mortar which may be easily manipulated by an operator.

A further object of the invention is the provision, in a mechanism for applying mortar, of a novel valve therefor.

A still further object of the invention is the provision, in a mechanism for applying mortar, of a novel gauge or guide member therefor.

Other and further objects of the invention will become apparent from a reading of the following specification, taken in conjunction with the drawings, in which:

Figure 1 is a side elevational view, partly broken away, of an embodiment of the invention shown in filling position.

Figure 2 is a front elevation view of the device shown in Figure 1.

Figure 3 is a side elevational view of Figure 2.

Figure 4 is a sectional view taken along line 4—4 of Figure 2.

Figure 5 is a view similar to Figure 4, but showing a certain element in another position.

Figure 6 is a fragmentary perspective view of one end of the apparatus.

Figure 7 is a fragmentary sectional view disclosing certain details of the invention, and

Figure 8 is a sectional view taken along line 8—8 of Figure 3.

Generally, there is provided a mortar applicator consisting of an open topped container having a lip along one edge whereby the same may be filled in the manner of a scoop, that is to say, by moving the same into a mass of mortar upon a mortar board with the lip in contact with the board. The container tapers toward the bottom end which is provided with a normally open

2

valve adapted to be closed by levers adjacent a pair of carrying handles mounted at either end of the container. A guide bar is pivotally mounted upon the container and is adapted to be utilized upon either side of a wall relative to the position of the operator, without the necessity of reversing the mechanism in the operator's hand.

Referring more particularly to the drawings, 10 there is shown therein a container having a pair of downwardly converging sides 10 and 11 having an integrally formed vertically extending base member 12 for the side 10 and a parallel base member 13 suspended adjacent the side 11 from end members 14 by means of brackets 15 in spaced relation to the side 11.

The side 10 is provided with an upwardly extending lip 16 and handle grips 17 are carried by brackets 18 mounted on each of the end members 14.

15 A valve plate 19 is carried at the lower ends of arms 20 which are pivotally connected at their upper ends to the upper ends of the side members 14 adjacent the side 11, as indicated at 21. 20 The valve plate 19 extends horizontally and is adapted to reciprocate through the opening 22 between the side 11 and base member 13.

25 A rod 23 is pivotally connected, as indicated at 24, to each of the arms 20 and is adapted to 30 slidably engage in a bracket 25. The rod is provided with a stop member 26 upon one side of the bracket 25 and a stop member 27 at the other side thereof. A compression spring 28 surrounds the rod 23 and is adapted to normally urge 35 the stop members 27 away from the bracket 25.

30 A guide member 29 is suspended below the base members 12 by a pair of arms 30 pivotally and centrally connected at their upper extremities 40 adjacent the upper edge of the end members 14, as indicated at 31 and a pair of outwardly extending abutments 32 is provided at either side of the device for limiting the pivotal movement of the arms 30. The end members 14 do not 45 extend downwardly to enclose the base members 12 and 13 and thus they are provided with open ends.

The arms 30 have each affixed thereto an inwardly extending horizontally disposed arm 33 having its free end bent to form a finger piece 34.

50 In operation, it will be apparent that in order to load the device, the operator thereof will first 55 grip the handles 17, one in each hand, and then place the device on side 10 with the lip 16 in

contact with the top of a mortar board 35 and thereupon close the valve 19 by applying pressure to the finger grips 34 with his fingers. The device may now be operated as a scoop to fill the same with mortar, as illustrated in Figure 1.

It is then returned to an upright position as shown, for example, in Figure 2. With the valve still closed, the base members 12 and 13 are placed upon one edge of the top of a wall section 36 to which it is desired to apply mortar with the guide member 29 bearing against the side of the wall section. The finger grips 34 are now released and the springs 28 will cause the valve 19 to open and the mortar to fall by gravity to the top of the wall within the confines of the base members 12 and 13. The device is then moved along the wall, the guide members 29 keeping the base members at the edge thereof and mortar will continue to be applied to the wall, the open ends of the base members allowing the same to pass therethrough in uniform thickness and width. To treat the opposite upper edge of the wall in the same manner, it is only necessary to move the device directly away from the operator and press the guide member against the opposite side of the wall, whereupon the process may be repeated.

While but one form of the invention has been shown and described herein, it will be readily apparent to those skilled in the art that many minor modifications may be made without departing from the spirit of the invention or the scope of the appended claims.

What is claimed is:

1. A device of the character described comprising an open topped container having a downwardly tapered body adapted to contain mortar, a valve at the lower end of the body to control the flow of mortar therethrough, a pair of base members for limiting the width of a mass of mortar passing through the valve and means adapted to selectively maintain the front and rear edges of the base members in parallel relation to the top of a wall, said means comprising a bar extending horizontally below the base members, arms attached at their lower ends to the bar and pivotally connected at their upper ends to the container and outwardly extending detents carried by the container for limiting the movement of said arms.

2. A device of the character described comprising an open topped container having a downwardly tapered body adapted to contain mortar, a lip formed integrally with one of the upper edges of a container whereby the container may be used as a scoop to fill the same, a valve at the lower end of the body to control the flow of mortar therethrough, a pair of base members for limiting the width of a mass of mortar passing through the valve and means adapted to selectively maintain the front and rear edges of the base members in parallel relation to the top of a wall, said means comprising a bar extending horizontally below the base members, arms attached at their lower ends to the bar and pivotally connected at their upper ends to the container and outwardly extending detents carried by the container for limiting the movement of said arms.
3. A mortar applicator comprising an open topped container having a narrow mortar dispensing slot in the lower part thereof, a valve operative transversely through the lower portion of the container to cut off mortar from said slot, handles at the end of the container for manually supporting the container and control means situated adjacent at least one of the handles and being operatively connected with said valve means, whereby the valve can be operated, while the handles are gripped, and an adjustable guide, for the container and underlying the lower portion of the container, for guiding the container along a wall section, said guide being swingable from one side of the slot to the other side, when working opposite edges of a wall section.

WILLIAM C. KLOMAN, JR.
